UNITED STATES PATENT OFFICE.

ADAM NICKEL, OF NEW YORK, N. Y.

DAMPER-ACTION FOR GRAND PIANOS.

SPECIFICATION forming part of Letters Patent No. 588,594, dated August 24, 1897.

Application filed May 3, 1897. Serial No. 634,828. (No model.)

To all whom it may concern:

Be it known that I, ADAM NICKEL, of New York city, county and State of New York, have invented an Improved Damper-Action 5 for Grand Pianos, of which the following is a specification.

This invention relates to an improved damper-action for grand pianos, and more particularly to the means for supporting the sustaining-rod that holds the temporarily-raised dampers away from the strings during the depression of the sustaining-pedal. Heretofore this sustaining-rod was either connected to the piano-action proper (in contradistinction 10 to the damper-action) or it was separately secured to the piano-case. Both of these constructions are objectionable, the former because it renders access to and adjustment of the sustaining-rod difficult, and the latter because it necessitates additional labor in securing such rod in place. I propose to adjustably secure the sustaining-rod to the same brackets that support the damper-rail and lifters, so that the whole of the damper-action forms 15 a connected entirety which may be readily slipped into the case and which allows full exposure and adjustment of the sustaining-rod previous to the insertion or upon the withdrawal of the piano-action proper.

20 In the accompanying drawings, Figure 1 is a side elevation of my improved damper-action; Fig. 2, a vertical section on line 2 2, Fig. 3; Fig. 4, a sectional plan; Fig. 5, a detail showing the engagement between sustaining-rod and lifter; and Fig. 5, a detail cross-section on line 5 5, Fig. 2.

25

The letters A A represent a pair of damper-brackets adapted to be screwed to the piano-case and supporting the damper-rail 40 a, pivoted thereto at a', and an additional back rail a². To the rail a are pivoted at b' the damper-levers b, that carry the lifters b², and are engaged at their forward ends by keys B. To limit the upward motion of the 45 damper-levers, there is screwed to an upper arm A' of bracket A the block-rail d.

e is the sustaining-rod, which is provided with a longitudinal flange, feather, or nose e', and is adapted to be rocked in its bearings 50 upon the depression or release of the sustaining-pedal. This rocking motion is transmit-

ted to the rod e by means of a lifter f engaging a crank f', rigidly connected to the rod. After a key is depressed a pressure upon the sustaining-pedal will throw the flange e' upward and beneath a preferably spring-hung nose c of the lifter b², so that such lifter is maintained in its raised position as long as the sustaining-pedal remains depressed. Upon the release of the sustaining-pedal the 55 sustaining-rod is rocked downward by the pedal-spring to withdraw its flange out of the path of nose c and permit a descent of the damper.

I propose to adjustably secure the sustaining-rod e to the same brackets A that carry the damper-rail a, so that in this way all the parts of the damper mechanism form a connected entirety.

To carry the invention into effect, I provide each bracket A with a slotted forwardly-projecting arm A², that receives the shank of an upright screw g. This shank is preferably flattened, Fig. 5, to prevent rotation within the slotted arm. The upper end or 70 head of screw g is perforated to constitute the bearing for the trunnion of rod e, which is thus free to rock backward or forward. In order to permit vertical adjustment of the rod e, the screw g carries nuts g' g² above and 75 below arm A², respectively, which on being manipulated in the usual manner cause the screw to be raised or lowered. A horizontal adjustment of the rod e may be effected by a set-screw h, which passes through the screw-shank g within the slot of arm A² and im- 80 pinges against the base of such slot.

It will be seen that with my construction all the parts of the damper-action, including damper-rail, block-rail, and sustaining-rod, 90 are supported by the common brackets A and form one connected mechanism, which may be readily slid into the case. After the damper-action has been inserted and secured in place, the sustaining-rod is fully exposed and 95 freely accessible for adjusting purposes. Not until this adjustment has been effected is the piano-action proper secured in place in front of the damper-action. Furthermore, as all the parts of my improved damper-action are 100 disconnected to each other the action can be delivered by the action-manufacturer to the

piano-manufacturer in a complete state ready for insertion into the case.

What I claim is—

1. In a damper-action for grand pianos, the combination of damper-brackets, with vertically and horizontally adjustable bearings secured thereto, and with a sustaining-rod hung within such bearings, substantially as specified.
2. In a damper-action for grand pianos, the combination of a damper-bracket, having a forwardly-extended slotted arm, with a screw having a perforated head and adjustably supported by the arm, and with a sustaining-

rod hung within the perforated screw-head, 15 substantially as specified.

3. In a damper-action for grand pianos, the combination of a damper-bracket having a forwardly-extending slotted arm with a flattened perforated screw, a sustaining-rod hung 20 within the perforation of the screw, and with a pair of nuts and a set-screw for causing a vertical and horizontal adjustment of the screw, substantially as specified.

ADAM NICKEL.
